UNITED STATES PATENT OFFICE

EDWIN FITCH NORTHRUP, OF PRINCETON, NEW JERSEY, ASSIGNOR TO AJAX ELECTROTHERMIC CORPORATION, OF AJAX PARK, NEW JERSEY, A CORPORATION OF NEW JERSEY

MAGNETIC RETURN CIRCUIT

Application filed October 22, 1930. Serial No. 490,514.

My invention relates to methods and apparatus for eliminating stray field about an inductor coil, which may be the inductor of an electric furnace, a reactor or any similar 5 coil.

A purpose of my invention is to increase the effectiveness of a compensator coil in eliminating stray field about an inductor by reducing the reluctance of the magnetic path between the inductor and the compensator coil, through interposing magnetic material between the inductor and the compensator coil.

A further purpose is to employ a material of high magnetic permeability and low electrical conductivity to cooperate with a compensator coil in eliminating stray field about an inductor.

A further purpose is to interthread magnetic material of suitable electrical properties between the turns of an inductor coil or of a compensator coil or of both coils, with or without continuity of the interthreading material from coil to coil.

A further purpose is to employ for such interthreading a magnetic material which, in layers of a thickness not greater than the distance between adjacent turns of a coil, has an electrical break-down voltage higher than the voltage drop between individual turns of the coil.

A further purpose is to disperse electrically conducting magnetic particles throughout material of low electrical conductivity, making the concentration of magnetic particles so low that the electrical conductivity of the resultant mass is low, while its magnetic permeability is high.

A further purpose is to separate magnetic particles for use about an inductor coil by particles of heat insulation or refractory.

A further purpose is to place about an inductor coil an uncompressed nonhomogeneous mass of particles, some of which are magnetic and electrically conducting and others 45 of which are of high electrical resistance.

A further purpose is firmly to position an inductor coil and a compensator coil with respect to one another and to a furnace frame work by packing solidly between the two coils a magnetic mass of high electrical resistance.

A further purpose is to pack against or desirably between the turns of an inductor coil nonmagnetic material toward the inside edge and magnetic material toward the outside edge so that the magnetic field about the turns will encounter low reluctance at the outside of the coil and higher reluctance at the inside of the coil.

A further purpose is to surround a compensator coil with magnetic heat insulation to protect the coil from the heat of the furnace and to concurrently eliminate stray field.

A further purpose is to construct one wall of an inductor coil cooling spray chamber of magnetic material and preferably embed a compensator coil within the magnetic material.

A further purpose is to reduce the reluctance of the magnetic path between opposite turns of a focus inductor, or between an inductor and a focus inductor, or about an inductor outside of a focus inductor, desirably placing magnetic material of high electrical resistance in physical contact with the turns or continuously between the turns, or in both places.

Further purposes will appear in the specification and in the claims.

My invention relates both to the methods involved and to apparatus by which the methods may be carried out.

I have preferred to illustrate my invention by a few forms only among the many in which it may appear, selecting forms which are practical, efficient, and reliable, and which at the same time well illustrate the principles involved.

Figures 1 and 2 are vertical central sections

of diagrammatic furnaces embodying my invention.

Figure 1a is a fragmentary diagrammatic view, showing the magnetic field about an individual inductor and compensator turn of Figure 1 where no magnetic material is present.

Figure 1b corresponds to Figure 1a, but shows the field when magnetic material is located between the inductor and the compensator.

Figure 3 is a fragmentary view corresponding to a portion of Figure 2, but showing a somewhat different variation.

Figure 4 is a vertical central section of a slightly different structure embodying my invention.

Figure 5 is a diagrammatic vertical central section of a furnace to which my invention has been applied.

Figure 6 is a modified fragment of Figure 5.

Figure 7 is a vertical central section of one form of complete furnace embodying my invention.

Figure 8 is a top plan view of a focus inductor furnace to which my invention has been applied.

Figure 9 is a section upon the line 9—9 of Figure 8.

Figure 10 is a modified fragment of Figure 9.

Figure 11 corresponds generally to Figure 10, but shows the magnetic material differently placed.

In the drawings similar numerals indicate like parts.

In my Patent No. 1,744,983, for inductor furnace, granted January 28, 1930, I have described the principles of eliminating stray field by means of a compensator coil placed outside of the inductor and inductively or directly connected in the circuit in any one of a number of ways there shown.

At any given instant the current carried by the compensator coil will be opposite to that in the adjacent turns of the inductor, either because the compensator coil is directly and oppositely connected in the circuit of the inductor coil or because the compensator coil is inductively coupled with respect to the inductor and therefore carries an opposite induced current.

In Figures 1, 2, 3, 4, and 5, I show a crucible 20 surrounded by an inductor coil 21, shown in most of the figures as formed of hollow flattened water cooled tubing. It will be understood that the inductor coil may be of any of the well recognized types, whether solid or hollow, and no matter what the method of cooling and the electrical connections.

The inductor coil is surrounded by a compensator coil 22. In Figure 1 the inductor and compensator coils are connected elec-

trically in series by connection 23, so that the current flows through the two coils in opposite directions. Current is supplied from a source 24 through connections 25 and 26. The power factor is corrected by capacitative reactance 27.

In Figure 2 the compensator coil is inductively coupled to the inductor coil. Current is supplied directly to the inductor coil by the leads 25 and 26. The compensator coil is short-circuited by a connection 28.

The circuit of Figure 4 is intended to be identical with that of Figure 2 except that in Figure 4 the short-circuiting connection 28 for the inductively coupled compensator coil includes a capacity 29.

In Figure 5 the circuit of Figure 1 is diagrammatically illustrated.

The circuits here shown and others not shown are well known in the art of employing compensator coils, and those shown are described merely for completeness.

Considering only the inductor coil 21 and the compensator coil 22 of Figure 1, individual adjacent turns of each of which are shown at 21' and 22' in the diagrammatic view, Figure 1a, the current at a given instant may be assumed to be coming up in the inductor coil turn 21' and passing down in the compensator coil turn 22', as indicated by the dot and plus signs. Under these conditions, the field about the inductor turn 21' will be counterclockwise, while that about the compensator turn 22' will be clockwise.

The directions of the flux inside and outside the inductor turn 21' due to that turn are indicated respectively by the arrows 30 and 31. Similarly, the directions of the flux due to the compensator turn 22' inside and outside of that turn are indicated respectively by the arrows 32 and 33.

Thus it will be seen that, under any assumed conditions, the arrows 31 and 32, indicating the paths of flux travel between the inductor and compensator coils, are in the same direction, indicating that the fluxes cooperate in the space between the inductor and compensator coils. Due to the limited range of the compensator coil field, since it may be adjusted as to size and location, the amount of flux from the compensator coil which passes inside the inductor coil is negligible, so that the flux travel indicated by the arrow 30 inside the inductor coil is unopposed.

On the other hand, flux from the inductor coil which passes outside of the legitimate return circuit of the inductor coil, taking the path indicated by the arrow 34, is opposed and diminished or eliminated by the flux of the compensator coil whose path is indicated by the arrow 33.

Then it will be understood that the compensator coil assists the field of the inductor

coil in the space inside the compensator coil, but opposes and eliminates any stray field from the inductor coil outside of the compensator coil. The point at which the stray field is to be cut off and the extent of stray field elimination can very largely be determined by the location, construction and electrical characteristics of the compensator coil.

The above discussion has merely set forth 10 the well understood principles with regard to compensator coils. I have discovered that great advantage may be gained by interposing magnetic material continuously or magnetic material of high electrical resistance 15 between the inductor coil and the compensator coil.

In Figure 1 I illustrate the magnetic material at 35, consisting of a mass having low magnetic reluctance and high electrical resistance so as to avoid the development of 20 excessive eddy currents. I prefer to form the magnetic mass of magnetic particles dispersed throughout a nonmagnetic medium of high electrical resistance, as more fully 25 explained below.

The magnetic material is shown in the various figures as supported by a suitable non-magnetic shell 36, which takes different forms according to the special needs of 30 surface, and which may be eliminated altogether where the magnetic mass is self-sustaining, or is supported separately, as for example, by the frame structure of the furnace.

In Figure 1b I illustrate turns 21' and 22' 35 from the inductor and compensator coils on the left hand side of Figure 1, as shown in Figure 1a. However, differing from Figure 1a, magnetic material 35 is placed between the inductor and compensator coils.

40 The distribution of the lines of force inside the inductor coil will not be affected by the magnetic material, but most of the lines of force which otherwise would take the path indicated by 34, outside of the compensator 45 coil and opposed by the lines of force indicated by 33, will now follow a path inside instead of outside of the compensator coil.

A relatively weak field, represented by the arrow 34', will in some instances tend to pass 50 beyond the compensator coil, but will be eliminated completely and with ease. Thus where, in Figure 1a, many of the lines of force go into stray field which the compensator coil is obliged to eliminate, in Figure 55 1b, due to the increased permeability of the path through the magnetic material 35, these same lines of force take a path between the compensator and inductor coil, assisted by the lines of force from the compensator coil.

60 It will thus be understood that by my magnetic material I am able to increase greatly the effectiveness of stray field elimination produced by a given compensator coil. Similarly, I may obtain stray field elimination, 65 equal to that which occurs when no magnetic

material is used, by employing a much smaller compensator coil, fewer compensator coil turns, or a lower compensator coil current.

In addition to these advantages in more complete and easy field elimination, I also have a magnetic return path of much smaller reluctance for my inductor coil. Similarly, the reluctance of the magnetic return path of the compensator coil is also decreased, and the return paths of the inductor and compensator coils assist one another, since both are in the same direction, as before.

The effect of the compensator coil 22 and the magnetic material 35 acting together is then to reduce the magnetomotive force necessary to pass a given magnetic field across the return circuit of the inductor coil.

70 My invention may be applied by placing magnetic material between the turns of the inductor coil or of the compensator coil or of both, and by providing a complete magnetic path between the compensator and inductor coils.

75 In Figure 2 the magnetic material 35' extends between the turns of the inductor coil as at 37, thus increasing the permeability of the magnetic path between the turns.

80 As will be explained below, the magnetic material for this use must of course be of high electrical resistance, as otherwise the turns would be short-circuited. Even if insulating material were placed about the turns to prevent short-circuiting, excessive eddy currents would build up in the material 35', were it of low resistance. In the form of 85 Figure 2 the magnetic return circuit has very low reluctance, so that most of the lines of force will remain in the material 35', and relatively few will need to be cut off by the compensator coil.

90 In Figure 3 the magnetic material 35² is placed between the turns of the compensator coil at 38, but not between the turns of the inductor coil. In this case the inner part 95 of the return circuit of the inductor coil will take place in nonmagnetic material, but the outer part of the return circuit will take place in magnetic material, and the bulk of the lines of force will take the return path through the magnetic material. Here also, 100 relatively few lines of force will pass beyond the magnetic material 35² to be eliminated by the compensator coil.

105 In Figure 4, the magnetic material 35³ is placed between both the inductor and compensator coil turns, as at 37' and 38' respectively. The magnetic material 35³ provides a complete magnetic path from the inductor coil to the compensator coil, so that none of the return magnetic circuit of either the inductor or compensator coil need take place 110 in nonmagnetic material, as would be the case in Figures 1, 2 or 3.

115 The form of Figure 4, besides being desirable for theoretical reasons, is advantageous 120

in construction because both the inductor and compensator coils are firmly positioned by magnetic material 35³, and, if the magnetic material have heat insulating properties, the 5 compensator coil may also be protected from the heat of the furnace by the magnetic material.

In Figure 4 I illustrate an outer furnace casing 39, which may desirably consist of 10 steel, and be protected from excessive inductive heating by the magnetic material 35³ and the compensator coil 22. This illustration is intended to be merely conventional, since in many cases the furnace structure will 15 consist principally of nonmagnetic materials such as asbestos board, with frame members of steel or of some other metal.

In Figure 5 I illustrate a crucible surrounded by inductor and compensator coils and 20 supplied with current from a suitable source E. Magnetic material 35 has been placed between the compensator and inductor coils, and heat insulation 40 is located around the crucible inside the inductor coil. The magnetic material itself here also performs a 25 heat insulating function. This arrangement is desirable because magnetic material should not be used inside the inductor coil, as it would cut off lines of force from the charge. 30 On the other hand, magnetic material may desirably be used between the inductor and compensator coils, and this same material here reduces the conduction of heat to the compensator coil. This is later explained 35 in more detail.

In Figure 6 I show a supposed line of juncture between the heat insulation 40 and the magnetic material 35 at the inductor coil turns 21². From this figure it is seen that 40 the heat insulation extends part way through the inductor coil from the inside as at 41, while the magnetic material extends part way through from the outside as at 42, forming a line of juncture 43 with the heat insulation. Thus the inductor coil is solidly supported and electrically insulated by the materials 40 and 35, and yet its magnetic field 45 will be unaffected inside, but will be distorted inwardly on the outside.

The magnetic material will perform other 50 functions in addition to that of increasing the permeability of the magnetic return circuit. In Figure 7 I illustrate a furnace construction in which magnetic high resistance 55 material assists the compensator coil in cutting off stray field from the inductor coil, insulates the compensator coil against excessive heat from the charge and confines the cooling medium in a chamber surrounding 60 the inductor coil.

The furnace of Figure 7 comprises a crucible 20 surrounded by heat insulation 40' of any suitable material, preferably finely divided refractory tamped in place. A 65 retaining shell 44 of miconite supports the

refractory. The inductor coil 21³ is wound from solid stock, and is firmly held by an air dried shell 45 of molded refractory, preferably consisting of a mixture of 70% of sand, 20% of thermolith (chrome ore with a binder) and 10% of sodium silicate.

Between the turns of the inductor I place suitable insulating layers 46.

The inductor coil 21³ is coated with a 75 water-proofing material which is also desirably an electrical insulator and which will stand a temperature of several hundred degrees Fahrenheit. I have used a so-called white porcelain which is sprayed on and of which there are several on the market, one under the name of "Insalute". This coating, shown at 47, protects against leakage of liquid through the coil and against short-circuiting of the coil.

The water-proof coating 47 is in turn 80 covered by a suitable tape 48 which has a wick action in carrying water or steam to the surface of the inductor coil. I find asbestos to be a desirable material for the tape 48.

Outside of the inductor coil I provide a 85 vapor space 49 in which steam may develop when cooling water is vaporized. Water carried through the coil 22² is distributed 90 through spray nozzles 50 against the tape 48 and the covered inductor coil. The coil 22² is short-circuited or otherwise suitably connected in the circuit to serve as a compensator coil, eliminating stray field from the inductor as in the case of a typical compensator coil.

About and chiefly inside of the turns of the compensator coil I place a suitable high 95 resistance magnetic material 35⁴, which assists the compensator coil to eliminate stray field as in the forms explained above.

It will be noted particularly that the relation of the magnetic material to the inductor and compensator coils in Figure 7 is 100 similar to that diagrammatically illustrated in Figure 3, except that magnetic material is placed outside the compensator coil (as well as within it), thus causing part of the flux outside the compensator coil to take a path through the magnetic material, opposing any stray field from the inductor which may pass beyond the compensator coil.

The magnetic material 35⁴ may desirably 105 contain heat insulating particles between the magnetic particles, so that the compensator coil will be protected from heat developed in the furnace.

As the inductor coil becomes highly heated, 110 water will vaporize in the chamber 49, absorbing as it does so its latent heat of vaporization from the inductor coil and surrounding parts. The magnetic material will in this case serve as an outer wall for the chamber 49, with or without a water-proof coating 115 on its inner surface. Thus it is possible to 120

gain the advantage of having magnetic material between the inductor and compensator coils without sacrificing the space required for the chamber 49 and without covering the inductor coil 21^a.

Steam and water from the chamber 49 are free to escape through the openings 51 and 52. The opening 52 also allows the bus bars 53 and 54 from the opposite ends of the inductor coil to pass to external contacts, one of which is shown against the bracket 55, insulated by the asbestos block 56 from the steel frame parts 57 and 58.

The outer furnace casing 59 of steel or other suitable material is insulated from the frame parts by the asbestos block 60 and the asbestos rings 61, 62, 63 and 63'. A brick base 64 supports the entire furnace. Suitable heat insulation 65 has been packed around the top of the crucible and around the spout 66.

In Figures 8 and 9 I show the application of my invention to a focus inductor furnace. The use of focus inductors is explained in my patents, No. 1,378,187 for focus inductor furnace, granted May 17, 1921, and No. 1,378,188 for ladle heating by high frequency currents, granted May 17, 1921.

The crucible 20 is surrounded by heat insulation 40 held in place by a shell 67, preferably of miconite. Outside of the shell may be seen the opposite turns 68 and 69 of the focus inductor 70.

The inductor coil 21^a surrounds the focus inductor and is water cooled through connections 71 and 72. Water connections to the focus inductor are shown at 73 and 74. Current is passed through the inductor coil from leads connected at 75 and 76, and this serves to induce opposite current in the adjacent turns 69 of the focus inductor. The current in the inner turns 68 of the focus inductor has the same instantaneous direction as that in the inductor.

In furnaces of this type I have previously proposed placing laminated magnetic return circuits at spaced circumferential intervals from one another, extending vertically outside of the inductor coil and inter-threading between the opposite sides of the focus inductor coil at spaced points about the coil. These magnetic return circuits have been incomplete in that they are close to the coils at a few points only, and have not always been convenient on account of the space limitations between and around the focus inductor and the inductor.

By my present invention I avoid all such laminated magnetic return circuits and use magnetic material of high resistance at the points desired in relation to the focus inductor and inductor. Since I will ordinarily employ my magnetic material in finely divided form, it may be placed in any location, no matter what the amount of space available and the shape of the space.

In Figure 9 I show magnetic material 35^b between the turns of the focus inductor and extending completely around the furnace except where broken at 77 by the ends of the focus inductor. The magnetic material 70 35^b rests upon the furnace base 78 and is covered by a refractory ring 79.

I also place magnetic material 35^c around the outside of the inductor to reduce the reluctance of the magnetic return circuit of 75 the inductor.

Thus it will be seen that in Figure 9 I provide a path of low reluctance between opposite sides of the focus inductor and also a path of low reluctance for the return circuit of the inductor. It will be evident, however, that magnetic material may be arranged in other ways about a focus inductor furnace. In Figure 10 I show magnetic material 35^d between the inductor 21^a and the outer turns 80 69 of the focus inductor. In this case a path of low reluctance exists between the inductor and the focus inductor.

In Figure 11 magnetic material 35^e is placed around the inductor turns 21^a, but no 90 magnetic material is placed within the inductor or around the focus inductor. Obviously, other variations and modifications may be employed.

It has previously been suggested that finely 95 divided magnetic material containing high resistance particles be employed for a magnetic return circuit.

I have recognized that the electrical resistance of such material may be desirably increased by reducing the concentration of low resistance magnetic particles in a mass consisting partially of nonmagnetic particles of high electrical resistance, so that the frequency of contact between the electrically 100 conducting particles will be reduced.

In the past, when such magnetic particles have been employed, the mass has been compressed. This I have discovered to be undesirable, since it places the electrically conducting particles in close contact and greatly reduces the electrical resistance of the mass. I will therefore ordinarily avoid compressing the mass, and in any case I will make the concentration of electrically conducting particles low enough with respect to the compression so that the resultant mass will have 110 a high electrical resistance.

To increase the electrical resistance of the mass, I increase the percentage of particles of high electrical resistance, thus spacing the electrically conducting magnetic particles from one another by particles of high resistance.

Depending upon the purpose for which my 125 magnetic material will be used, I vary the character of the nonmagnetic particles. For example, where I desire the resultant mass to be a fairly good conductor of heat (although a poor conductor of electricity), I use high 130

resistance particles of good heat conductivity. On the other hand, where I desire the mass to have heat insulating properties, I use high resistance particles of poor heat conductivity, as for example refractory particles such as zircon.

The characteristics of the magnetic material from an electrical standpoint will of course vary with the strength of the magnetic field, with the strength of the electric field at the point where the magnetic material is to be placed, and with the frequency of the electrical current. I preferably operate at a point upon the magnetic saturation curve for my magnetic material below complete saturation, in order to obtain the maximum permeability consistent with high electrical resistance. Thus I increase the concentration of magnetic particles as much as possible without decreasing the electrical resistance below the amount permissible.

Where the current in the inductor is of high frequency, I require high electrical resistance in my magnetic material as a composite in order to avoid the development of excessive eddy currents. Because, by regulating the magnetic particle size, and average distance of separation I may increase at will the electrical resistance of the magnetic mass, my invention is particularly applicable to high frequencies, where the need of reducing eddy currents is much greater than at lower frequencies.

The magnetic particles will ordinarily be iron filings or similar particles. They may be of course particles of very high permeability, as for example transformer iron or high silicon steel.

Where the mass need not have heat insulating properties, the high resistance particles may consist of zinc oxide.

The relationship between the size of the low reluctance particles and that of the high resistance particles in the mass is important. If one sort of particles is considerably larger than the other sort, the smaller particles will fit into the interstices of the larger particles, and direct particle contact from one low reluctance (low resistance) particle to another will not be eliminated. Then, under this condition, the electrical resistance of the mass will be correspondingly low. If the high resistance particles are also heat insulators, the mass nevertheless will be a poor heat insulator.

However, if both sorts of particles are of comparable size, the high resistance particles will space the low reluctance (low resistance) particles from one another, and the mass will have high resistance. Also, if the high resistance particles are good heat insulators, the mass will be a good heat insulator in that case.

I therefore will preferably make all par-

ticles of the non-homogeneous magnetic mass of the same size.

It is not necessary to use particles of high electrical resistance at all in order to obtain a magnetic mass of high electrical resistance. The magnetic particles themselves may be coated with a high resistance film, described by me as an illustration but not claimed as a species by me, in order to increase the contact resistance from particle to particle, thus increasing the electrical resistance of the mass. This has the advantage that the magnetic permeability will be higher than in a magnetic mass containing nonmagnetic high resistance particles, because permeability depends upon nearness or separation of the magnetic particles rather than upon cleanliness of contact between them.

The high resistance coating for the surface of the magnetic particles may be a layer of iron oxide formed on the surface, or a passive outer layer obtained by treating the iron particles with cold concentrated nitric acid.

However, in its best form it consists of separate insulating material applied to the surfaces of the particles. A satisfactory material is porcelain enamel, of which there are several on the market, one being known as "Insalute". Insalute has the advantage of resisting a considerable rise in temperature, a condition inevitable in a magnetic material which must be placed close to a hot charge. The magnetic mass may also have heat insulating properties secured by a particle coating which is a heat insulator. Insalute is again advantageous for this purpose.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:—

1. In a stray field eliminator for inductor coils, a compensator coil surrounding the inductor coil and instantaneously carrying current in the opposite direction from that of the current in the inductor coil and finely divided magnetic particles forming a mass between the compensator and inductor coils occupying continuously a considerable circumferential extent about the inductor.

2. In a stray field eliminator for inductor coils, a compensator coil surrounding the inductor coil and instantaneously carrying current in the opposite direction from that of the current in the inductor coil and magnetic material continuously annularly surround-

ing the inductor coil between the compensator and inductor coils.

3. In a stray field eliminator for inductor coils, a compensator coil surrounding the inductor coil and instantaneously carrying current in the opposite direction from that of the current in the inductor coil and finely divided magnetic particles annularly surrounding the inductor coil between the compensator and inductor coils.

4. In a stray field eliminator for inductor coils, a compensator coil surrounding the inductor coil and instantaneously carrying current in the opposite direction from that of the current in the inductor coil and magnetic material of high electrical resistance between the compensator and inductor coils.

5. In a stray field eliminator for inductor coils, a compensator coil surrounding the inductor coil and instantaneously carrying current in the opposite direction from that of the current in the inductor coil and finely divided magnetic material of high electrical resistance between the compensator and inductor coils.

6. In a stray field eliminator for inductor coils, a compensator coil surrounding the inductor coil and instantaneously carrying current in the opposite direction from that of the current in the inductor coil and magnetic material of high electrical resistance annularly surrounding the inductor coil between the compensator and inductor coils.

7. In an electric induction furnace, an inductor coil, a compensator coil surrounding the inductor and adapted to carry current instantaneously in an opposite direction from that of the current carried by the inductor coil and magnetic material annularly surrounding the inductor coil between the compensator and inductor coils.

8. In an electric induction furnace, an inductor coil, a compensator coil adapted to carry current instantaneously in an opposite direction from that of the current carried by the inductor coil and finely divided magnetic particles between the compensator and inductor coils.

9. In an electric induction furnace, an inductor coil, a compensator coil surrounding the inductor and adapted to carry current instantaneously in an opposite direction from that of the current carried by the inductor coil and a non-homogeneous mass of magnetic particles mixed with high resistance particles between the compensator and inductor coils.

10. In an electric induction furnace, an inductor coil, a compensator coil surrounding the inductor and adapted to carry current instantaneously in an opposite direction from that of the current carried by the inductor coil and magnetic material between the turns of the inductor coil and outside of the inductor coil between the compensator and inductor coils.

11. In an electric induction furnace, an inductor coil, a compensator coil surrounding the inductor and adapted to carry current instantaneously in an opposite direction from that of the current carried by the inductor coil and magnetic material of high electrical resistance between the turns of the inductor coil and annularly surrounding the inductor coil between the compensator and inductor coils.

12. In an electric induction furnace, an inductor coil, a compensator coil surrounding the inductor and adapted to carry current instantaneously in an opposite direction from that of the current carried by the inductor coil and a magnetic core inserted between the turns of the compensator coil.

13. In an electric induction furnace, an inductor coil, a compensator coil surrounding the inductor and adapted to carry current instantaneously in an opposite direction from that of the current carried by the inductor coil and a magnetic core between the turns of the compensator coil and within the compensator coil.

14. In an electric induction furnace, an inductor coil, a compensator coil surrounding the inductor and adapted to carry current instantaneously in an opposite direction from that of the current carried by the inductor coil and magnetic material of high electrical resistance between the turns of the compensator coil.

15. In an electric induction furnace, an inductor coil, a compensator coil surrounding the inductor and adapted to carry current instantaneously in an opposite direction from that of the current carried by the inductor coil and magnetic material of high electrical resistance between the turns of the inductor and compensator coils.

16. In an electric induction furnace, an inductor coil, a compensator coil surrounding the inductor and adapted to carry current instantaneously in an opposite direction from that of the current carried by the inductor coil and magnetic material between the turns of the inductor and compensator coils and annularly between the inductor and compensator coils.

17. In an electric induction furnace, an inductor coil, a compensator coil surrounding the inductor and adapted to carry current instantaneously in an opposite direction from that of the current carried by the inductor coil and magnetic material of high electrical resistance between the turns of the inductor and compensator coils and annularly between the inductor and compensator coils.

18. In an electric induction furnace, an inductor coil, a compensator coil surrounding the inductor and adapted to carry current instantaneously in an opposite direction from that of the current carried by the in-

- ductor coil and magnetic material extending annularly around the outside of the compensator coil.
19. In an electric induction furnace, an inductor coil, a compensator coil surrounding the inductor and adapted to carry current instantaneously in an opposite direction from that of the current in the inductor, heat insulation within the inductor and against its turns on the inside and magnetic material outside of the inductor and against its turns on the outside, whereby the reluctance of the magnetic path is unchanged on the inside, but is decreased on the outside of the inductor to assist the compensator in reducing stray field. 70
20. In an electric induction furnace, an inductor coil, a compensator coil surrounding the inductor and adapted to carry current instantaneously in an opposite direction from that of the current in the inductor, heat insulation within the inductor and between its turns toward the inside and magnetic material outside of the inductor and between its turns toward the outside, whereby the magnetic return circuit is distorted inward so that the compensator may more easily eliminate stray field. 75
21. In an electric induction furnace, an inductor coil externally exposed for heat transfer, nozzles adapted to spray a cooling medium in heat transferring relation to the surface of the inductor coil and an annular magnetic core spaced from the inductor a sufficient distance to permit application to the inductor of the cooling medium, whereby the cooling medium is externally confined by the magnetic material and the stray field from the inductor is short-circuited through it. 80
22. In an electric induction furnace, an inductor coil externally exposed for heat transfer, a compensator coil surrounding the inductor and instantaneously adapted to carry current in the opposite direction from that of the current in the inductor, spray nozzles, for application of a cooling medium in heat transferring relation to the outside of the inductor and magnetic material within the compensator coil annularly surrounding and spaced from the inductor a sufficient distance to permit application to the inductor of a cooling medium. 85
23. In an electric induction furnace, an inductor coil externally exposed for heat transfer, a hollow water-carrying compensator coil surrounding the inductor, spray nozzles communicating with the interior of the compensator coil at intervals along its length and directing water in heat transferring relation to the outside of the inductor and magnetic material of high electrical resistance about the compensator coil outside of the spray nozzles. 90
24. In an electric induction furnace, co- 95
- axial outer and inner, focus inductor coils and finely divided magnetic particles between the focus inductor coils for improving the flux path. 100
25. In an electric induction furnace, an inductor coil, a focus inductor within the inductor coil having opposite portions of individual turns radially spaced from one another and magnetic material between the opposite sides of the individual focus inductor turns conforming to the path of those turns. 105
26. In an electric induction furnace, an inductor coil, a focus inductor within the inductor coil having opposite portions of individual turns radially spaced from one another and magnetic material of high electrical resistance between the opposite sides of the individual focus inductor turns and following the course of the turns. 110
27. In an electric induction furnace, an inductor coil, a focus inductor within the inductor having opposite portions of individual turns radially spaced from one another and finely divided magnetic particles between the turns of the focus inductor. 115
28. In an electric induction furnace, an inductor coil, a focus inductor within the inductor having opposite portions of individual turns radially spaced from one another and a heat insulating mass containing magnetic material of high electrical resistance annularly surrounding the focus inductor. 120
29. In an electric induction furnace, an inductor coil, a focus inductor within the inductor having opposite portions of individual turns radially spaced from one another, magnetic material of high electrical resistance between the opposite sides of the individual turns of the focus inductor and following the course of these turns and magnetic material surrounding the inductor. 125
30. In an electric induction furnace, an inductor coil, a focus inductor within the inductor coil having opposite portions of individual turns radially spaced from one another and magnetic material between the inductor and the outside of the focus inductor annularly surrounding the focus inductor. 130
